[57] CLAIM

The ornamental design for a portable folding tub, as
shown and described.

DESCRIPTION

FIG. 1 is a front elevation of a portable hot tub showing
my new design, the back elevation being a mirror im-
age;

FIG. 2 is a top plan view thereof;

FIG. 3 is a side elevation thereof; and,

FIG. 4 is a perspective view thereof.

The bottom of the portable folding tub is plain and
unornamented.
